(57) **CLAIM**

The ornamental design for a depilatory applicator, as shown and described.

DESCRIPTION

FIG. 1 is a front and left side perspective view of a depilatory applicator showing, in vertical configuration, a first embodiment of our new design;

FIG. 2 is a front elevational view thereof;

FIG. 3 is a rear elevational view thereof;

FIG. 4 is a right side view thereof, the left side being a mirror image;

FIG. 5 is a top plan view thereof; and

FIG. 6 is a bottom plan view thereof.

FIG. 7 is a front and left end perspective view of a depilatory applicator showing, in horizontal configuration, a second embodiment of our new design;

FIG. 8 is a right end plan view thereof;

FIG. 9 is a rear plan view thereof; and,

FIG. 10 is a side view along the top portion of FIG. 9, the side view along the bottom portion thereof being a mirror image.
